COKE OVEN STRUCTURE

Fred Denig, Pittsburgh, Pa., assignor to Koppers
Company, a corporation of Delaware

Application August 5, 1937, Serial No. 157,461

8 Claims. (Cl. 202—151)

The present invention relates to horizontal coking retort ovens of the regenerative type and more especially to those that are provided with accessible passageways beneath the oven-supporting mat, such, for example, as those passageways wherein are found the distribution systems for the unpreheated underfiring gas that is supplied to the flame flues of the so-called underjet coking ovens.

10 In a battery of regenerative coking retort ovens the coking chambers are generally disposed in alternation with flued heating walls along its lengthwise dimension. Beneath the coking chambers and the heating walls are checkerbrick-filled regenerative spaces wherein underfiring gases may be preheated before they are introduced into the flame flues, the heat for such purpose being recovered from the combustion-products subsequent their leaving the heating flue system and within the regenerative spaces. Periodically the direction of gaseous flow in the regenerators and in the flued heating walls is reversed so that that heat recovered from the outflowing combustion-products and stored in the checkerbrick during one interval of the reversal period, is released to the inflowing fuel gases during the subsequent interval. Beneath the bottom of the regenerators is a structural mat that extends beneath the whole battery structure for which it serves as a support. This supporting-mat for the battery may rest either directly on the ground surface or be elevated therefrom on piers in such manner as to provide accessible passageways therebeneath wherein supply and control devices for supervising the operation of the ovens may be positioned.

An object of the present invention is the provision of means whereby gases may be flowed between the heating flues of the heating walls and the regenerative spaces in accurately and facilely controlled amounts that are conveniently regulable from the afore-mentioned accessible passageways beneath the battery-supporting mat.

A further object of invention is to furnish means that will enable coke oven operators to regulate and control from the relatively cool region beneath the battery-supporting mat the quantities of gases that are flowed between the regenerators and each of the heating flues with which they communicate so that during operation the flues will be each assured of having those quantities of gases flowed therethrough as are preferred in consideration of their relative positions in the heating wall and without subjecting the operators to the laborious task of making

adjustments from the tops of highly incandescent flues.

A further object of invention is the provision of an easily operable means for the foregivn objectives and purposes that will neither operate as an impediment to the flow of the gases after they have entered the heating flues nor create undesirable back pressures therein.

The invention has for further objects such other improvements and such other operative advantages or results as may be found to obtain in the processes or apparatus hereinafter described or claimed.

In horizontal coking retort ovens of the regenerative type, each heating flue of a heating wall is communicably connected with at least one therebeneath positioned regenerative space, and in those instances where the oven structure is adaptd for operation as a "gas oven" with extraneously produced underfiring gas of lower thermal content, which requires preheating for its effective combustion, each flue communicates with at least two separate regenerative spaces the one of which is utilized to preheat underfiring gas while the other is used to preheat the air for its combustion. In general, communication between the heating flues and the regenerators is provided by canals or ducts that connect at their lower parts with the upper parts of the regenerators and at their upper ends port into the lower parts of the heating flues. These passageways between the flues and the regenerators commonly pass through the tops or capitals of those vertical pillar walls that separate the entire regenerative space beneath the oven floors into individual regenerators extending lengthwise of the coking chambers, and that also support the upper part of the battery structure. The pillar walls each at their lower parts rest on the battery-supporting mat and at their tops support the masonry of the flued heating wall and the oven sole immediately above. They are formed from courses of bricks, and those bricks at the upper part of said pillar walls are appropriately shaped to provide the above-mentioned passageways between the regenerators and the flues.

According to the present invention there is supplied for each of the heating flues of a coking oven heating wall and at a point adjacent the top of its associated pillar wall, a movable refractory brick that is adapted for actuation from beneath the battery-supporting mat and in such manner that said brick may be employed to modify as preferred the effective cross-section of the passageways that interconnect the heating flues

with the regenerative spaces therebeneath thereby making it possible to vary optionally the rate at which gases may flow from the regenerators into the heating flues individually, under the influence of the stack-draft, without that awkwardness and tedium attending the adjusting of sliding bricks or the angling for port regulating media positioned at the bottom of flues that are highly incandescent. In its preferred form the 10 adjustable gas-flow regulating brick of the invention is positioned in the brickwork adjacent the top of the oven pillar wall and forms a section of the side-walls of the passageways or ducts that communicably connect the regenerators and 15 heating flues where it is held in position by a stem-like section that is disposed to rest slideably in a vertically extending shaft that reaches from the top of the pillar wall downwardly therethrough and through the battery-supporting mat and into the accessible passageways beneath said mat. Within each such shaft is slideably disposed a refractory rod or tube which is supported therein by means of a threaded bolt, or the like, that is in turn supported by and 20 adapted to travel through a securing member also located in the battery basement. The refractory rod may be formed in sections, if preferred, thereby facilitating its installation in the vertical shaft, and it should be of adequate total 25 length to transmit movement of said screw-bolt to that stem-like section of the moveable brick which retains the latter in its designed position. By means of this improvement the coke oven operator is provided an implement whereby 30 the effective cross-sections of those ducts that interconnect regenerators and heating flues, can be optionally varied by appropriate adjustments on regulatory screw-bolts conveniently accessible in the battery basement, thus providing means 35 40 that are adapted to permit expeditious regulation from that station of preheated air and preheated underfiring gas that enter the flame flues and without encountering the inconveniences of high temperatures at which metal adjusting implements 45 lose their rigidity, as is the case where control measures must proceed from the tops of the heating flues. Additional advantages of the instant improvement reside in the facts that it is possible to effect the preferred adjustments 50 with dispatch and that it offers a means of obtaining an improved refinement in the regulation of a battery's underfiring.

In the accompanying drawings forming a part of this specification and showing for purposes 55 of exemplification a preferred apparatus and method in which the invention may be embodied and practised but without limiting the claimed invention specifically to such illustrative instance or instances:

60 Figure 1 is a crosswise vertical section through a coke oven battery embodying features of the present improvement, said battery comprising coking ovens of the so-called underjet type in which unpreheated underfiring gases are distributed to the heating flues from a distribution system therefor positioned in a basement located beneath the battery-supporting mat, the section A—A of the view being taken longitudinally through a coking chamber and along the line 65 A—A of Figure 2, whereas the section B—B is taken through a heating wall and a pillar wall and along the line B—B of Figure 2;

70 Figure 2 is a vertical sectional elevation taken longitudinally of a coke oven battery, portions 75 being shown broken away for clearness of illus-

tration, and a part of the section being taken in a portion of the battery in the plane indicated by the lines II—II and the other part of the section being taken through another portion of the battery in the plane IIa—IIa of Figure 1;

75 Figure 3 is an enlarged view of a fragment of the section taken on the line II—II of Figure 1 and illustrated in Figure 2 and showing certain details of the present invention and their arrangement with respect to the regenerator ports 10 at the bottom of the heating flues and to the pillar walls of the battery;

Figure 4 is fragmentary vertical sectional view taken crosswise of the battery along the line B—B of Figure 2, showing an enlarged fragment 15 of that part of the section B—B of Figure 1 which involves the pillar wall, rich underfiring-gas conduits and the improvement offered by the present invention;

Figure 5 is a horizontal section taken along the 20 line V—V of Figure 4;

Figure 6 is an enlarged view of the means provided by the invention and employed to adjust that amount of the total cross-sectional area of the ducts connecting the regenerators and the 25 heating flues, which is made available for the flow of gases therebetween; and

Figure 7 is a perspective view of the structure shown in enlarged section in Figure 3 but on 30 smaller scale.

The same characters of reference designate the same parts throughout the several views of the drawings.

Referring now to the drawings: the invention as shown in the several views of the drawings is 35 embodied for purposes of exposition in a coke oven battery of the underjet type which is also susceptible of being operated as a "gas oven" at which times heating of the coking-chamber walls is effected by means of a gas of lower calorific 40 value that requires a preheating step before being introduced into the flame flues; certain of the regenerators being utilized for that purpose. The flues of any heating wall at one side of a coking 45 chamber are communicably connected at their upper ends with similarly disposed and grouped flues of the heating wall at the opposite side of said coking chamber by means of duct means that cross over the top of said chamber in the well-known manner of the Becker ovens of for 50 instance, his Patent 2,100,762, wherein the combustion-products or waste gases from any one heating wall are led into the upper ends of the heating flues at the opposite side of the intermediate coking chamber. The benefits provided 55 by the present improvement are not necessarily restricted to coke ovens of the design illustrated in the drawings but they can be realized in any regenerative coke oven battery that is supported on piers in such manner as to provide accessible 60 passageways therebeneath.

The coking retort oven battery shown in the drawings embodies in its construction a plurality of crosswise elongated heating walls 11, 11 and a plurality of intermediate elongated vertical coking chambers 12, 12. The heating walls 11 form the side walls of the respective coking chambers 12 as shown particularly in Figures 1 and 2 and are supported in the present instance by heavy supporting pillar walls 13, 13 that extend crosswise of the battery and are located as shown in Figure 2, beneath their respective heating walls. The pillar walls 13 serve both to support the heating walls and to divide the regenerative space beneath the heating walls and the coking cham- 75

bers into a plurality of gas-tight individual regenerators that extend crosswise of the battery and in substantial parallelism with the heating walls. Each of the regenerators positioned between the pillar walls 13 is further sub-divided into a regenerator pair by the regenerator division wall 14 which serves to support the coal charge in the coking chamber 12 directly above it and is in addition of such substantial and 10 gas-tight construction that gases may be maintained under relatively different pressures on the opposite sides of said division walls 14 so that the flow of different underfiring media through the checkerbrick contained in these different regenerator chambers 15 may be maintained without 15 leakages from one chamber to the other taking place. Each regenerator of a regenerator pair is furnished with an individual sole flue 16 that communicates by means of a plurality of ducts 17 with the checkerwork above, said ducts operating to promote a uniform distribution throughout the regenerator chamber of the gases introduced into the ends of sole flues. The vertical heating flues 18 of the heating walls each communicate 20 with two regenerators 15, that are located on opposite sides of the pillar walls 13, by means of ducts 19 through which the gases, flowed over the regenerator checkerbrick from the sole flues, pass into the lower part of said heating flues. 25 Beneath the regenerators is the battery-supporting mat 20 that is itself supported by piers 21 above the ground level thereby providing passageways 22 in which access can be had to the mat from beneath as well as such of the operating accessories as may be positioned there. 30 For the introduction into the heating flues of unpreheated underfiring gases a distribution system in the battery basement is provided. The arterial rich gas supplying-main 23 communicates with a reservoir of rich gas outside the battery structure. Rich gas is flowed therefrom in quantities regulated by gas-cock 24 into distributor header 25, whence said gas passes into ducts 26 that rise vertically through the battery-supporting mat and the pillar walls 13 to terminate at the lower part of the heating flues at gas-ports 27. A distributor header 25 is provided for each heating wall and a duct 26 rises therefrom to each flue therealong. The air destined 40 for admixture and combustion with unpreheated underfiring gas that is introduced into the heating flues through said ducts 26, is flowed into all the sole channels 16 from regulable flow-boxes positioned at the outer ends thereof (but not shown) and subsequent its distribution by ducts 45 17 over the checkerbricks, contained in regenerators 15 for preheating purposes, said air enters the burning flues at their lower ends through ducts 19; that air which is preheated in those 50 regenerators adjacent to and on opposite sides of the same pillar walls 13 is introduced into the heating flues of any one wall through ports 28 that are common to both regenerators and their ducts 19, as is clearly shown in Figures 3 and 7. 55 The combustion-products produced by the burning of the rich gas and preheated air rise through flues 18 and pass into short horizontal ducts 29 whence they enter similar heating flues in the wall on the opposite side of a coking chamber by way of cross-over ducts 30 to flow downwardly 60 into other communicating regenerators in which waste-heat is accumulated from the combustion-products as they flow downward and outward therethrough to stack means. 65

75 Heat liberated by the reactions of combustion

is transferred through the heating walls to the coal charge that has been previously introduced through charging holes 31 into the coking chambers 12 that are closed at each end by refractory-lined doors 32. The gases and vapors of distillation are carried away through ascension pipes 33. Periodically the direction of gaseous flow through the regenerator and heating flue systems is reversed and the burning flues become the non-burning ones and the inflowing become the out-flowing regenerators, and vice versa. 10

At such times as the battery in which the invention is embodied is being operated for the production of gas of relatively high thermal content, the battery may be underfired with gas of 15 lower heating value than that resulting from the carbonization, and the rich gas supply to the heating flues is cut off by closing valves 24 that deliver gas to the distributor-headers 25, and the underfiring gas of low heating value, such as producer or blast furnace gas, is introduced into regenerators for a preheating step, prior to its entering the heating flues. This method of operation is too well known in the prior art to need further comment here, but during such periods 20 of operation, in the battery shown in the drawings, it is the preferred procedure that during a regenerative heating cycle those regenerators whose tops are communicably connected by heating flues that are interconnected, for gas flow 25 purposes, by cross-over ducts that extend upward and over the top of an oven adjacent said flues, shall have said regenerators so arranged in respect of the regulation and control devices for 30 the waste-heat, the air and the fuel gas that 35 an air regenerator is always interposed between the combustion-products regenerators and the regenerator for preheating fuel gas, and that the regenerators for carrying inflowing fuel gas and combustion air are adjacent to and on opposite 40 sides of the same pillar wall 13, (a circumstance which will be considered hereinafter in respect of the present improvement).

Under certain operating conditions it is for several reasons highly desirable to regulate the quantities of air and underfiring gases that are introduced into the individual heating flues because, as is appreciated by those experienced in the art, the heat requirements of each of the plurality of heating flues along an oven wall varies somewhat in relationship to the distance it is removed from the oven face where the effects of radiation are most pronounced. Likewise, sharp changes in the duration of the carbonization period or changes in the type of gas used for underfiring may make it advisable or even necessary, from considerations of thermal economy as well as uniform heating of the coking chamber walls from ends to ends thereof, to alter the amounts of underfiring gases flowed into the separate flues, 50 so that the provision of means whereby the effective cross-section of the ducts that lead from the regenerators to the heating flues can be altered with great convenience and facility, will be an 55 advantageous contribution to the art. 60

In the coking retort battery illustrated in the drawings, two regenerators adjacent opposite sides of the same pillar wall 13 are each connected with a heating flue 18 by means of ducts 19, 19. A short distance below the bottom of the heating 70 flue, the two said ducts gradually converge into a common short duct through which gases from each of the pair of regenerators enter the heating flue. The cross-sectional area of ducts 19 gradually diminishes as they approach their point of 75

convergence where the masonry of the division wall which separates them terminates in a flat surface 35. Shaft 34 extends from surface 35 downward the entire height of the pillar wall and 5 through the battery mat to open in the passageways therebeneath. Shiftable brick 36 which is formed with inclined sides where it forms a part of the walls of ducts 19 and also has a stem-like part 37 attached to its underside, rests loosely 10 on the surface 35 of pillar wall 13 as a sort of finial thereto; the part 37 being of such size as to be easily moveable in the duct 34 at all temperatures of operation. According to the invention said shaft 34 contains a plurality of refractory rods 38, or if preferred pipe-like shapes, that are fitted for up and down movement therein by means of the supporting screw-bolt 39 that has a threaded section whereby it is secured in a correspondingly threaded hole of the battery-supporting structural beam 40. With appropriate turning of the head of screw-bolt 39 by any suitable means, said screw-bolt can be caused to travel upwards or downwards in beam 40 and to respectively raise or lower the train of refractory 20 rods 38 which in turn operates to move brick-shape 36 in a corresponding direction by its pressure against the lower part of section 37. As is clearly shown in Figure 3, the raising of brick 36 upward to some such position as is shown 25 30 by the dotted lines, will gradually decrease the distance between the surface of said brick and the masonry forming the upper-walls at throat 41 of conduits 19, thereby reducing the free-way that is available for gas-flow therebetween and 35 simultaneously decreasing the volume of gaseous media that is permitted to enter the heating flue from the regenerators during a given interval. The member 39 can be turned through a large arc and yet cause the shiftable brick 36 to travel only 40 a relatively short distance, thus the improvement offered by the invention provides easily operable means for establishing accurate adjustments of the effective cross-section of ducts 19 and as a result effects an improved refinement in 45 control of the rate at which gases are delivered to the heating flues.

As hereinabove mentioned, at such times as it is desired to operate as "gas ovens" the ovens of the battery in which the invention is embodied, 50 one of the two regenerators 15 adjacent opposite sides of the pillar wall 13 will be periodically operating to preheat a gas of low calorific value with the result that during such intervals one duct of an adjacent pair of ducts 19 will be carrying preheated underfiring gas to the associated heating flue while preheated air is flowing upwards through the other. If then, under such circumstances of operation, shiftable brick 36 were elevated above division-wall surface 35 for 55 purposes of reducing the gas rate, a pre-mixing and combustion of preheated air and underfiring gases might take place in the interspace between and thus cause over-heating of the masonry there-adjacent, if provision were not made to circumvent it. This eventuality is overcome according to the invention by providing fin-like 60 projections 42 on opposite sides of stem 31 of shiftable brick 36, said projections being adapted to fit into slots 43 that are formed at the upper 65 part of the vertical shafts 34 in the pillar walls. These fin-like projections in effect operate as a means for extending upward the division wall between the conduits 19 when brick 36 is raised above the level of surface 35, as is clearly 70 apparent from Figures 3, 4 and 7.

That common section of a pair of conduits 19, 19, between their convergence and port 28 is formed with substantially vertical side walls and the maximum volume of gases permitted to flow therethrough from the regenerators into the heating flues at a given pressure differential is determined by a removable port-plug 44 having walls substantially parallel with the side-walls of said conduit section, so that the preheated gases enter the heating flues in the form of an annular ring 10 and with no tendency to be diverted from a stream-like flow-path by this port regulating means, which has been disclosed and described in an application for Letters Patent by Joseph van Ackeren applied for on May 14, 1936, and assigned Serial Number 79,669. Plug 44 is removably supported on brick-shape 36 by means of a lug 45 that is formed at one end thereof, said lug being also adapted to be received by socket 46 in the upper surface of the brick-shape 36. The 20 plug may be removed or replaced through a flue-inspection hole by means of a rod adapted to engage said plug after it has entered slot 47. It is of course obvious that the area of port 28 made available for the flowing of gases between the 25 heating flues and the regenerators may be varied by using port-plugs having cross-sections that bear various relationships to the total cross-section of the port opening.

An advantage resulting from the combination 30 of a port-plug of this type and of an adjustable refractory element in the masonry of a regenerator pillar wall by means of which the effective cross-section of conduits connecting heating flues and regenerators may be altered as preferred, 35 resides in the fact that such turbulence or eddying in the stream of issuing gases as may be promoted by the presence therein of said refractory element, will tend to be corrected by a concentrically positioned port-plug having side-walls 40 substantially parallel with those of the port-duct, so that gases entering the heating flue will be directed upwards in a substantially vertical flow-path which in the case of rich gas underfiring advantageously tends to delay combustion somewhat and thus lengthen the flame. It also does 45 not prevent some intermingling of preheated air and preheated underfiring gas before they enter the heating flues, thereby promoting more favorable heating conditions at the bottom of the 50 ovens than would otherwise obtain with gases of lower calorific values.

By reason of the present invention, the occasion for altering the effective cross-section of ports 28 after a battery embodying the improvement has been taken into operation will only infrequently arise since there can be initially chosen, for the individual heating flue when brick 36 is in lowered position, a port plug of such proportions relative to its port 28 that the maximum 60 gas requirement for the flue will be provided at the pressure differential obtaining between the flue and the regenerators, and any reduction in this requirement can be effectively and easily made through raising brick 36 that amount needed 65 to provide the necessary throttling effect, by simple turning of a threaded member that is conveniently accessible in the battery basement,

The invention as hereinabove set forth is embodied in particular form and manner but may 70 be variously embodied within the scope of the claims hereinafter made.

I claim:

1. In a coking retort oven having accessible 75 passageways beneath a supporting-mat therefor,

the combination of: a coking chamber having a flued heating wall there-adjacent and a regenerator therebeneath; regenerator duct means in the region of the juncture of the heating flue with the regenerator therefor, individually connecting the lower part of a heating flue of said wall with the upper part of said regenerator; an adjustable flow restricting element for the regenerator duct-means positioned between the lower part of 5 said heating flue and the upper part of said regenerator and adapted to modify the cross-sectional area of said regenerator duct means in such manner that gases flowed therethrough are susceptible of regulation independently of regenerator duct means for other heating flues of said heating wall; and adjustable regulating means extending downwardly from the flow restricting means into the accessible passageway and operative from beneath the oven-supporting mat for 10 actuating said flow restricting element to adjust the same from within the accessible passageway beneath the oven mat of the oven.

2. A coke oven having accessible passageways beneath a supporting-mat therefor; a coking chamber having a flued heating wall there-adjacent and a regenerator therebeneath; regenerator duct means, in the region of the juncture of the heating flue with the regenerator therefor, individually connecting the lower part of a heating 15 flue of said wall with the upper part of said regenerator; an adjustable flow restricting element for the regenerator duct means positioned between the lower part of said heating flue and the upper part of said regenerator and adapted 20 to modify the cross-sectional area of said regenerator duct-means in such manner that gases flowed therethrough are susceptible of regulation independently of regenerator duct-means for other heating flues of said heating wall; and adjustable regulating means extending downwardly from the flow restricting means into the accessible passageway and operative from beneath the oven-supporting mat for actuating said flow restricting element to adjust the same from within the accessible passageway beneath the oven mat of the oven; and in which the adjustable flow restricting element is a member that forms essentially a part of the duct walls of the regenerator duct means that communicably connect a heating flue with a regenerative space and in which the regulating means for said flow restricting element comprises a rod-like member that is adapted to be raised and lowered in said vertical shaft from beneath the oven-supporting 25 mat.

3. In a regenerative coking retort oven having a horizontally elongated coking chamber and on either side thereof vertically flued heating walls that are supported by pillar walls disposed to 30 rest on a supporting-mat having accessible passageways therebeneath, the heating flues of the heating walls being each communicably connected at their lower parts individually with the upper parts of regenerators that are positioned on opposite sides of said pillar walls by converging 35 regenerator ducts in the region of the juncture of the heating walls with the regenerators, the duct means to any one heating flue comprising separate duct portions leading from the separate 40 regenerator chambers and converging into, and entering the lower part of the heating flue through, an upper common port, in combination: for individual heating flues, a movable brick-valve-element that is positioned adjacent the 45 converging point of the lower walls of said duct 50 means and beneath their upper port; a vertical shaft extending from said accessible passageways upwards through a pillar wall and intersecting said duct means; means for retaining said movable brick-valve-element, adjustable with respect to said vertical shaft; and means, operative from beneath the over-supporting mat through said vertical shaft to actuate said movable brick-valve-element in a manner to modify the effective cross-sectional area of the duct means 55 that connect the heating flue and regenerators.

4. A regenerative coking retort oven as claimed in claim 3 and in which the movable brick is formed to constitute a segment of the walls of the duct means and is retained in position by a stem-like projection that is adapted to slideably fit into the vertical shaft of the pillar wall.

5. A regenerative coking retort oven as claimed in claim 3 and in which the movable brick is formed to constitute a segment of the walls of the duct means and is provided with lateral fin-like members that in effect operate to separate the converging portion of the duct means that lead from the respective regenerators when the movable brick is elevated in a vertical plane.

6. A regenerative coke oven as claimed in claim 3, and in which the movable brick-valve-element comprises a plug member adapted to modify the area of the upper common port which connects the converging duct portions of the converging duct means, said plug member being removably supported by and actuated with a lower damper member adapted to further modify the effective area of the duct means over the modification by the plug member when actuated for the purpose.

7. A regenerative coke oven having accessible passageways beneath a supporting-mat therefor; a coking chamber having a flued heating wall there-adjacent and a regenerator therebeneath; regenerator duct means, in the region of the juncture of the heating flue with the regenerator therefor, individually connecting the lower part of a heating flue of said wall with the upper part of said regenerator; an adjustable flow restricting element for the regenerator duct-means positioned between the lower part of said heating flue and the upper part of said regenerator and adapted to modify the cross-sectional area of said regenerator duct-means in such manner that gases flowed therethrough are susceptible of regulation independently of regenerator duct-means for other heating flues of said heating wall; and adjustable regulating means extending downwardly from the flow restricting means into the accessible passageway and operative from beneath the oven-supporting mat for actuating said flow restricting element to adjust the same from within the accessible passageway beneath the oven mat of the oven; and in which the adjustable flow restricting element comprises a lower member which itself forms a part of the walls of the duct means and is adjustable relative to the rest of the walls of the duct means to increase and decrease the cross-sectional area of the duct means, and an upper member movable with the movement of the lower member, removably mounted on the same for exchange with other like members of different sizes, and adapted to maintain a constant cross-sectional area in the portion of the duct means it dampens in any 60 adjusted position of the lower member.

8. A regenerative coke oven having accessible passageways beneath a supporting-mat therefor; a coking chamber having a flued heating wall there-adjacent and a regenerator therebeneath; 65

70

75

regenerator duct means, in the region of the juncture of the heating flue with the regenerator therefor, individually connecting the lower part of a heating flue of said wall with the upper part of said regenerator; an adjustable flow restricting element for the regenerator duct-means positioned between the lower part of said heating flue and the upper part of said regenerator and adapted to modify the cross-sectional area of said regenerator duct-means in such manner that gases flowed therethrough are susceptible of regulation independently of regenerator duct-means for other heating flues of said heating wall; and adjustable regulating means extending

downwardly from the flow restricting means into the accessible passageway and operative from beneath the oven-supporting mat for actuating said flow restricting element to adjust the same from within the accessible passageway beneath the oven mat of the oven; and in which the adjustable flow restricting element comprises a lower member which itself forms a part of the walls of the duct means and is adjustable relative to the rest of the walls of the duct means to increase and decrease the cross-sectional area of the duct means. 5 10

FRED DENIG.
